I. M. JACOBS & W. CRAMER,
ADJUSTABLE HOOD FOR MOTOR VEHICLES.
APPLICATION FILED OCT. 26, 1917.

1,273,616.

Patented July 23, 1918.

THE NORRIS PETERS CO., PHOTO-LITHO., WASHINGTON, D. C.

UNITED STATES PATENT OFFICE.

ISIDOR M. JACOBS, OF KANSAS CITY, AND WILLIAM CRAMER, OF ST. LOUIS, MISSOURI,
ASSIGNORS, BY MESNE ASSIGNMENTS, TO TRUCK, TRACTOR AND MANUFACTURING
COMPANY, OF ST. LOUIS, MISSOURI, A CORPORATION OF MISSOURI.

ADJUSTABLE HOOD FOR MOTOR-VEHICLES.

1,273,616.

Specification of Letters Patent. Patented July 23, 1918.

Application filed October 26, 1917. Serial No. 198,646.

To all whom it may concern:

Be it known that we, ISIDOR M. JACOBS and WILLIAM CRAMER, citizens of the United States, residing at Kansas City, in 5 the county of Jackson and State of Missouri, and St. Louis, State of Missouri, respectively, have invented certain new and useful Improvements in Adjustable Hoods for Motor-Vehicles, of which the following 10 is a specification.

This invention, while it may be of general utility, is especially designed in aid of the salvaged constructions contemplated by the application for patent Serial Number 15 163,652, filed by one of the joint inventors herein named, and has for its object the ready utilization of salvaged motor vehicle parts, and provides an extensible or telescoping hood for the engine, which hood, on 20 account of its capacity for telescoping or extension, can be readily adjusted to any length of engine.

In the accompanying drawings forming part of this specification in which like numbers of reference denote like parts wherever they occur,

Figure 1 is a sectional view on the line 1—1 in Fig. 2, looking in the direction of the arrows;

30 Fig. 2 is a side elevation; and

Fig. 3 is a sectional view in detail on the line 3—3 in Fig. 2, looking in the directions of the arrows.

The radiator 1 is supported in the chassis 2 in the usual manner and so also is the dash-board 3.

To the chassis 2 or a sill 3 thereabove are hinged at 4 the side members 5 of the engine hood, which are fastened by any suitable catches 6 to the lid member 7 or hood proper.

The hood proper 7 can be removed entirely when desired and the side members 5 let down so as to afford full and free access to each and every part of the engine.

So arranged as to telescope with the lid 7 and side members 5 are the end side members 8 and the end lid member 9, which are fitted to the dash 3 and attached by the plate 10 having the flanges 11 and the upturned lip 12 to the sills 3, or if desired directly to the chassis 2.

Rivets 13 attach lid 7 to flange 14 on the

radiator, which flange 14 is overlapped also by the side members 5 as well as by the 55 lid 7 and the member 9 is attached by screws 15 to the dash 3.

Lips 12 are attached by rivets 16 to the members 8. Lid 7 and member 9 are joined together by bolts 17 which pass therethrough and through plate 18, which is bracketed at 19 to dash 3. Plate 18 has a plurality of holes 20 in it, which allow the passage of a bolt 17 at any selected one of them; and thus when a short engine is to be 60 covered, the rear end of lid 7 will more closely approach dash 3 than when a longer engine is to be hooded. The holes 20 in plate 18, as shown in Fig. 2, permit of adjustment of the members 5 and 7 relative to 65 the members 8 and 9, in either direction. How this adjustment is made depends upon the length of the salvaged engine that is to be used, which also determines the location of the dash 3 relative to the radiator 1. It 70 will be observed that the downwardly folding sides 5 is a great convenience over constructions now common in which they fold up upon the lid or hood proper 75.

It will be understood that in using this 80 telescoping hood the radiator 1 is likely to be placed at the extreme front end of the chassis 2, but that the dash-board 3 can be placed at any suitable location relative to the radiator.

Having thus described this invention, we hereby reserve the benefit of all changes in form, arrangement, order, or use of parts, as it is evident that many minor changes may be made therein without departing 90 from the spirit of this invention, or the scope of the following claims.

We claim:

1. A longitudinally adjustable hood for motor vehicles, and means for rigidly securing said hood in any desired longitudinally adjusted position.

2. A longitudinally adjustable hood for motor vehicles comprising two parts, one adapted to overlap the other, and means for 100 rigidly securing said parts together in adjusted positions.

3. A longitudinally adjustable hood for motor vehicles comprising two main parts, the end of one main part adapted to overlap 105 the other main part, each of said main

parts being composed of separable parts, and means for connecting said main parts together in adjusted relation to each other.

4. A longitudinally adjustable hood for motor vehicles formed of two parts, one adapted to overlap the other, each of the said two parts being composed of three parts, one of the said three parts being a lid member and the other two side members.

5. A longitudinally adjustable hood for motor vehicles formed of two parts, one adapted to overlap the other, each of the said two parts being composed of three parts; one of the said three parts being a lid member and the other two side members, and means for fastening the said lid parts in fixed relation to each other.

6. A longitudinally adjustable hood for motor vehicles formed of two parts, one adapted to overlap the other, each of the said two parts being composed of three parts, one of the said three parts being a lid member and the other two side members, and adjustable means for fastening the said lid member parts in fixed relation to each other.

7. A longitudinally adjustable hood for motor vehicles formed of two parts, one adapted to overlap the other, each of the said two parts being composed of three parts, one of the said three parts being a lid member and the other two side members, means for fastening the said lid parts in fixed relation to each other, and means for attaching the said side members to the lid members.

8. A longitudinally adjustable hood for motor vehicles formed of two parts, one adapted to overlap the other, each of the said two parts being composed of three parts, one of the said three parts being a lid member and the other two side members, means for fastening the said lid parts in fixed relation to each other, and means for attaching both sets of side members to the chassis.

9. A longitudinally adjustable hood for motor vehicles formed of two parts, one adapted to overlap the other, each of the said two parts being composed of three parts, one of the said three parts being a lid member and the other two side members, means for fastening the said lid parts in fixed relation to each other, and means for

attaching the said side members to the chassis, the said means for one set of side members consisting of a sill-embracing flanged plate having a lip and means connecting the said lip to its respective side member.

10. A longitudinally adjustable hood for motor vehicles formed of two parts, one adapted to overlap the other, each of the said two parts being composed of three parts, one of the said three parts being a lid member and the other two side members, means for fastening the said lid parts in fixed relation to each other, and means for attaching the said side members to the chassis, the said means for one set of side members consisting of a sill-embracing flanged plate having a lip and means connecting the said lip to its respective side member; the other set of side members being attached to the chassis by hinges.

11. A longitudinally adjustable hood for motor vehicles formed of two parts, one adapted to overlap the other, each of the said two parts being composed of three parts, one of the said three parts being a lid member and the other two side members, and adjustable means for fastening the said lid parts in fixed relation to each other, the said adjustable means consisting of a plate having perforations therethrough and an arm at one end thereof whereby the same is attached to the dash-board and a bolt adapted to pass through both lid members and one of the perforations in the said plate.

12. A longitudinally adjustable hood for motor vehicles formed of two parts, one adapted to overlap the other, each of the said two parts being composed of three parts, one of the said three parts being a lid member and the other two side members, and adjustable means for fastening the said lid parts in fixed relation to each other; the said adjustable means consisting of a plate having perforations therethrough and an arm at one end thereof whereby the same is attached to the dash-board and a bolt adapted to pass through both lid members and one of the perforations in the said plate, the said adjustable means being plural and located on opposite sides of the lid members.

In testimony whereof we hereunto affix our signatures.

ISIDOR M. JACOBS.
WILLIAM CRAMER.
